No. 886,065.

PATENTED APR. 28, 1908.

J. T. NICHOLSON.
CONVEYER CHAIN.
APPLICATION FILED DEC. 12, 1907.

UNITED STATES PATENT OFFICE.

JESMOND T. NICHOLSON, OF WILKES-BARRE, PENNSYLVANIA.

CONVEYER-CHAIN.

No. 886,065.

Specification of Letters Patent.

Patented April 28, 1908.

Application filed December 12, 1907. Serial No. 406,130.

To all whom it may concern:

Be it known that I, JESMOND T. NICHOLSON, a citizen of the United States, residing at Wilkes-Barre, in the county of Luzerne 5 and State of Pennsylvania, have invented certain new and useful Improvements in Conveyer-Chains; and I do hereby declare the following to be a full, clear, and exact description of the invention, such as will enable others skilled in the art to which it appertains to make and use the same.

This invention relates to drive chains for conveyers and elevators; and it consists in the novel construction and combination of 15 the parts hereinafter fully described and claimed.

In the drawings, Figure 1 is a side view of a portion of a conveyer chain. Fig. 2 is a plan view of the same. Fig. 3 is a detail 20 view of the bracket for securing the flight-plate to the link. Fig. 4 is a sectional plan view of the joint. Fig. 5 is a cross-section through the eccentric portion of the pivot-pin showing portions of the links when arranged at a right angle.

A is a link provided at one end with a single-eye B, and at the other end with a double-eye C.

D is the conveyer flight-plate. This plate 30 is secured to the middle part of the link by a loop-shaped bracket d which straddles the link, and which is slid into engagement with a guide on the link. This guide preferably consists of lugs d' which project laterally 35 from the sides of the link.

The bracket d is provided with flanges E on its end portions, and e is an angle-shaped fastening-bar which is secured against the link so that the bracket cannot slide in its 40 guide. Bolts e' are provided for securing the said flight-plate and fastening-bar to the bracket d. This construction of the parts avoids the necessity of making holes or slots in the middle parts of the links.

The single-eye B has a round pin-hole F, and an eccentric end portion f. The double-eye C has round pin-holes G of the same size as the pin-hole F.

H is a cylindrical pivot-pin which is 50 slideable into engagement with the holes F and G when they are placed in line with each other. This pin has two eccentric portions h, and a head I. The head I has a flat portion i on one side which engages with a stop j on the 55 double-eye so that the pin is prevented from revolving when in position. A bearing k is

formed in the bottom of the jaw of the double eye for the eccentric portion f of the single-eye of the next adjacent link to engage with.

The links can only be coupled and uncoupled when placed at a right angle to each other as shown in Fig. 5. When arranged in this manner the round pin-holes are in line with each other, and the pivot-pin is then slid longitudinally into position. The links 60 are then turned into line with each other, and the eccentric portion f of the single-eye forces the holes of the double-eye into engagement with the eccentric portions h of the pivot-pin as shown in Fig. 4. The links 65 cannot become detached accidentally, but the pivot-pin may be taken out by placing one link at a right angle to the other so that the 70 holes of the said eyes are moved into line with each other.

What I claim is:

1. In a conveyer chain, the combination, with a link provided with a guide at its middle part, of a loop-shaped bracket which straddles the said link and which is secured 80 in the said guide, and a flight-plate secured to the said bracket.

2. In a conveyer chain, the combination, with a link provided with a guide at its middle part, of a loop-shaped bracket which 85 straddles the said link and engages with its said guide, a flight-plate, a fastening-bar which prevents the said bracket from sliding, and means for securing the said flight-plate and the said fastening-bar to the end 90 portions of the said bracket.

3. In a conveyer chain, the combination, with a link provided with a single-eye having an eccentric portion at its end, of a link provided with a double-eye having a bearing 95 which engages with the said projection and moves the holes of the said eyes out of line with each other, and a pivot-pin slideable into engagement with the said eyes and provided with an eccentric portion which engages with 100 one of the said eyes when the said holes are out of line and thereby prevents the said pin from sliding longitudinally.

4. In a conveyer chain, the combination, with a link provided with a single-eye having 105 an eccentric projection at its end, of a link provided with a double-eye having a bearing which engages with the said projection and moves the holes of the said eyes out of line with each other, a pivot-pin slideable into engagement with the said holes of the said eyes 110 and provided with eccentric portions which

engage with the holes of the said double-eye when the holes of the said eyes are moved out of line.

5. In a conveyer chain, the combination,
with a link provided with a single-eye having
an eccentric projection at its end, of a link
provided with a double-eye having a bearing
which engages with the said projection and
moves the holes of the said eyes out of line
10 with each other, a pivot-pin slidale into
engagement with the said eyes and provided

with an eccentric portion which engages with
one of the said eyes when their said holes are
out of line, and means for preventing the said
pin from revolving.

In testimony whereof I have affixed my
signature in the presence of two witnesses.

JESMOND T. NICHOLSON.

Witnesses:

W. B. YEAGER,
WARREN E. STRAW.
